UNITED STATES PATENT OFFICE.

JAMES A. GIESE, OF CHICAGO, ILLINOIS, ASSIGNOR TO THE ADAMS & WESTLAKE COMPANY, A CORPORATION OF ILLINOIS.

LOCK.

1,029,747.

Specification of Letters Patent. Patented June 18, 1912.

Application filed December 31, 1909. Serial No. 535,807.

To all whom it may concern:

Be it known that I, JAMES A. GIESE, a citizen of the United States, and resident of Chicago, county of Cook, and State of Illinois, have invented certain new and useful Improvements in Locks, of which the following is a specification, and which are illustrated in the accompanying drawings, forming a part thereof.

10 The invention relates to locks of that type wherein the locking bolt is normally concealed within a casing, and is projected to operative position by contact between the members to be united by it.

15 The object of the invention is to simplify and improve the construction of locks of the type described.

In the accompanying drawings:—Figure 1 is a detail side elevation of a door and its jamb, showing a lock embodying the features of the invention mounted thereon, some of the parts being broken away to the central plane of the lock, and the door being illustrated in the closed position; Fig. 2 is similar to Fig. 1, but shows the door partly opened; Fig. 3 is a detail side elevation of the door and the parts of the lock carried thereby, the cover plate of the lock being removed; and Fig. 4 is a plan sectional view taken on the line 4—4 of Fig. 1.

The invention is illustrated in the drawings in connection with a sliding door 10, such as is used upon street railway cars, and the like. The jamb against which the edge of the door abuts when closed is shown at 11.

The movable parts of the lock are preferably inclosed between cover plates, 12, 13, adapted to be applied to opposite sides of 40 the door 10, adjacent its forward edge. These cover plates are removably connected by screws 14, which, as shown, enter posts 15, mounted on the inner face of the plate 12, through apertures 16 in the plate 13. One of the plates, as 12, is provided with a flange 30, which extends across the front edge of the door. The jamb 11 of the door is recessed, as shown at 19, and carries a plate 17 which is provided with an aperture 18 in front of the recess. The usual knob spindle 20 extends through the door and is rotatably mounted in the plates 12, 13. Handles, as 21, 22, of a convenient form for

rotating the spindle 20 in pulling backwardly upon the door, are mounted upon the ends of the spindle. A single roll-back 55 23 is employed. As shown, it is mounted on the spindle 20 between the plates 12, 13, and normally rests against a stop 24.

The bolt is designated by the numeral 25, and is provided with a hooked, forward end 60 26. The shank of the bolt is slotted, as shown at 27, to receive the hub 28 of the roll-back 23. When the bolt 25 is retracted, it is entirely concealed between the plates 65 12, 13, as shown in Fig. 2 of the drawings. When advanced, as shown in Fig. 1 of the drawings, its hooked end 26 projects through an aperture 29 in the flange 30 of the plate 12, to enter the recess 19 in the 70 door jamb 11, and engage the shoulder of the aperture 18 in the plate 17, for securing the door 10 in the closed position.

A spring, as 31, is employed for advancing the bolt 25. As shown, this spring is 75 coiled about a pivot post 32, mounted on the plate 12, and reacts between a stop 33 and a lever 34. The lever 34 is pivoted on the post 32 and bears upon the bolt 25, as by engaging a stud 35, formed on the bolt. 80 A spring latch 36 is provided for securing the bolt 25 in the retracted position illustrated in Fig. 2 of the drawings. As shown, this spring latch takes the form of a bell crank lever pivotally mounted upon the 85 plate 12, as at 37, and having upon the end of one of its arms, a hook 38 for engaging the stud 35 on the bolt.

Provision is made for releasing the catch 36 to permit the bolt 25 to be projected by 90 the spring 31 when the door strikes the jamb in closing. As shown, a plunger 39 is pivotally connected to one of the arms, as 41, of the latch member 36, and extends forwardly therefrom into an aperture 95 42 provided in the flange 30. The forward end of the plunger 39 has a sliding engagement with the walls of the aperture 42, and its face is normally flush with the outer surface of the flange. When the door 10 approaches the closed position, the forward end of the plunger 39 is engaged by an appurtenance of the jamb 11, as a stud 43, formed on the jamb plate 17 to raise the latch 36 and release the bolt 25. A spring 100 44 controls the latch 36 and normally re-

tains the plunger 39 in its advanced position. This spring is most conveniently coiled about the stud 33, which serves as a stop for the spring 31 and reacts between 5 the pivot post 32 and the rear end of the plunger 39.

The roll-back 23 reacts upon the bolt 25 through a lever 45, which is pivotally mounted upon the plate 12, at 46, and bears 10 upon the stud 35 in opposition to the lever 34. A spring 47 bears upon the foot of the lever 45 to normally retain the roll-back 23 and spindle 20 in a position corresponding to an upright position of the knobs 21, 22. 15 As shown, this spring is coiled about a stud 48 formed on the plate 12 and reacts upon a fixed support, as a shoulder 49, formed on the inner face of the plate 12.

A stop lug 50 is provided for limiting the 20 movement of the bolt 25. As shown, this stop lug projects into the path of the bolt 25 from the inner face of the plate 12 in such a position that it is engaged by the hooked end 26 of the bolt 25 when the bolt 25 is in the retracted position, and enters a notch 51, formed in the under side of the bolt in front of the slot 27, when the bolt is advanced. The initial pressure of the lever 45 upon the stud 35 for retracting the bolt 30 is resisted by the stud 50, and the latter then acts as a fulcrum upon which the bolt tends to tilt. As the rearward end of the bolt is prevented from downward movement by the spindle 20, the rocking action is communicated to the forward end, raising it over the stud 50. Further pressure, by means of the lever 45, retracts the bolt to the position shown in Fig. 2. Should the door have been drawn back from the jamb when the retracting action is commenced, so that the hook 26 of the bolt rests firmly against the shoulder of the striker plate aperture, the bolt being slightly out of contact with the stud 50, this striker plate shoulder will serve as the fulcrum and cause the bolt to rise until it is freed therefrom. Should the bolt be accidentally projected while the door is open, the stud 50 will have the effect of causing the automatic engagement of the bolt with 50 the striker plate shoulder by preventing the bolt from being pushed inwardly by pressure upon its outer end. This action is rendered possible by the rounding or beveling of the nose of the bolt, as shown. By means 55 of this arrangement the stud 50 receives a considerable part of the strain applied to the bolt 25 by an attempt to open the door without releasing the bolt from the jamb plate 17. In the construction shown and 60 described, the bolt 25 is raised from engagement with the jamb plate 17, by pressure applied to either of the knobs 21, 22, for opening the door. When the bolt has been completely withdrawn, the stud 35 is engaged by the latch 36, and the bolt is thus

retained in a retracted position in which it is completely concealed within the casing formed by the plates 12, 13, and the flange 30, until the latch 36 is released by contact of the forward end of the plunger 39 with the stud 43 formed on the jamb plate 17. 70

If desired, key-controlled means may be employed for preventing rotation of the spindle 20 to release the bolt 25.

As shown, the roll-back 23 is provided 75 with a rearwardly projecting arm 52, and a stop 53 is slidingly mounted on the plate 12, to be moved into and out of the path of the arm 52 in the usual way by a key (not shown), adapted to be entered from either 80 side of the door through key openings 56 in the plates 12, 13 and 54.

The various parts of the lock are most conveniently maintained in operative relation upon the plate 12, and the studs 32, 33 85 and 48, by means of an intermediate cover plate 54, applied to the ends of the studs 32, 33 and 48 by screws, as 55.

I claim as my invention—

1. In a lock for sliding doors and the like, in combination, a casing, a jamb plate having a shoulder, a stud projecting from the face of the jamb plate, an oscillatable and reciprocable bolt having a hooked end carried by the casing and movable between 95 positions in which it is concealed within the casing and in which its hooked end projects from the casing to engage the shoulder of the jamb plate, respectively, a projecting spring acting on the bolt, a latch for securing the bolt in the retracted position, a trip engageable with the stud on the jamb plate for releasing the latch, means for oscillating and retracting the bolt, and key-controlled means for preventing the oscillation of the 105 bolt.

2. In a latch, in combination, a casing, a reciprocable and oscillatable hooked bolt housed within the casing having a backwardly facing shoulder, a fixed abutment 110 carried by the casing and engageable with the shoulder when the bolt is advanced, and a retracting lever engageable with a laterally-extending arm on the bolt.

3. In a lock, in combination, a reciprocable hooked bolt having its inner end longitudinally slotted, an oscillatable pivot extending through the slot, an arm projecting laterally from the bolt in the direction opposite from that of the hook, a retracting 120 lever engageable with the arm and an arm projecting from the pivot and engageable with the retracting lever.

4. In a lock, in combination, a hooked bolt having its inner end longitudinally slotted 125 and having a backwardly facing shoulder projecting in the same direction as its hook, a pivot extending through the slot, an arm projecting laterally from the bolt oppositely from the shoulder and hook, a retracting 130

lever engageable with the arm, and a fixed abutment engageable with the shoulder when the bolt is advanced.

5. In a lock, in combination, a reciprocal cable and oscillatable hooked bolt, a socketed keeper having an inwardly directed shoulder, an arm projecting laterally from the bolt oppositely from the hook thereof,

a retracting lever engageable with the arm, and a key-controlled detent for preventing 10 the oscillation of the bolt.

JAMES A. GIESE.
